CLAIM

The ornamental design for an aerosol spray actuator button, substantially as shown and described.

DESCRIPTION

FIG. 1 is a perspective view of an aerosol spray actuator button showing my new design;
FIG. 2 is a front elevational view;
FIG. 3 is a top plan view;
FIG. 4 is a rear elevational view;
FIG. 5 is a side elevational view, that of the opposite side being a mirror image thereof; and
FIG. 6 is a bottom plan view.

FIG. 1

FIG. 4

FIG. 2

FIG. 5

FIG. 3

FIG. 6
